Patented June 3, 1924.

UNITED STATES PATENT OFFICE.

TROWBRIDGE MARSTON, OF MORRISTOWN, NEW JERSEY, AND HERBERT E. SERNER,
OF NEW YORK, N. Y., ASSIGNORS TO KAUMAGRAPH COMPANY, OF NEW YORK, N. Y.,
A CORPORATION OF NEW YORK.

MACHINE FOR STAMPING LEATHER OR OTHER ARTICLES.

Application filed November 1, 1921. Serial No. 512,128.

To all whom it may concern:

Be it known that we, TROWBRIDGE MARSTON and HERBERT E. SERNER, citizens of the United States, and residents, respectively, of 5 Morristown, in Morris County, State of New Jersey, and New York city, in the county and State of New York, have invented certain new and useful Improvements in Machines for Stamping Leather or Other Articles, of which the following is a specification.

This invention relates to the application of transfer or decalcomania stamps to articles of various kinds such as calf skins and 15 is intended to provide a reliable and efficient mechanism for quickly and readily impressing the successive stamps formed on a carrier strip of tissue paper or other material to successive pieces of fabric or to 20 different portions of the same fabric.

In its general features it comprises a reciprocatory or oscillatory head carrying strip-holding and feeding devices for intermittently feeding the stamp-carrying strip 25 a predetermined distance at each cycle of operations and hot pressing the same against the fabric carried by a work-supporting bed. As the to and fro movements of the head 30 controls the necessary movements of the mechanism the machine can be operated by a foot pedal or by power, leaving the hands free to manipulate the pieces of work to be stamped.

This and other characteristic features of 35 the invention will be particularly explained in this specification and will be defined in the claims hereto annexed.

In the accompanying drawings is illustrated a simple and efficient form embodying 40 the principles of this invention, in which:

Figure 1 is a side elevation of the complete assembled machine in normal position.

Figure 2 is a front elevation at right angles to the plane of Figure 1.

Figure 3 is an enlarged detail end elevation of that side of the head carrying working parts.

Figure 4 is an enlarged central cross section through the head.

Figure 5 is a front elevation partly in section showing the head; and

Figure 6 is a detail face view of the clutch.

A work table 1 is provided with a work-

supporting bed or plate 2 on which the article to be stamped is placed, and has also a suitable upwardly projecting bracket 3 provided with bearings for supporting the parallel link arms 5 and 6 whose free ends are pivotally connected to the stamping head 7 by means of the transverse shafts 5^b and 6^a. The head 7 comprises the side members with transverse cross-bar 7^a provided with a handle 7^d and carries at its bottom a presser plate 7^b which may be heated in any suitable or well-known manner by steam, electricity or otherwise.

Extending transversely through the sides of the head 7 and supported in suitable bearings is a rotatable shaft 9 carrying heads 21 forming the end supports of a drum or feed roller 20. As best shown in Figure 5, one end of the head is provided with a large flanged opening to which is secured a supporting disk or plate 7^c which carries the mechanism for actuating the feed roller and also the brake mechanism to be hereinafter described.

An upper or idler feed roller 30 mounted on swinging arms 31 pivoted to transverse shaft 32 cooperates with the feed roller 20 in feeding the tissue paper or other strip which carries the material forming the stamps at short intervals throughout its length.

According to the particular form of the device shown and described herein it is the intention that the stamp strip should be at rest on the downward movement of the presser or head and then be fed forward an appropriate distance to bring the next stamp into stamping position on the upward movement of the head. It is also preferred that the movement of the head itself shall cause the actuation of the feeding mechanism so as to secure perfect correspondence between their respective movements.

The long stamp strip is wound on a supporting reel 4 from which it is unwound and carried partly around transverse guide bars 35, 36, then along underneath the yielding holder or presser foot 37 whose middle portion is cut away as shown in Figure 4 to allow the hot presser plate 7^b to pass through directly into contact with the stamp-carrying portion of the strip. The presser foot 37 is provided with an upwardly turned portion 38 to properly guide the strip and

present it to the feed roller 20 around which it is passed about half way and then reversely turned to pass back over the transverse bar 5^b with its free end as shown at 5^w, dropped over the tissue roll or coil carried by the reel 4 so that the mere contact with the intermittently rotating coil of the feed strip serves to carry away the waste or used portion of the strip into any conveniently placed waste receptacle.

The presser foot or tape-holding member 37 is carried by short plungers 39 which extend upward through openings in the bottom piece of the head 7 to permit vertical movement of the presser foot. Coil springs 40^a serve to keep the presser foot depressed some distance below the hot presser in order to prevent contact of the stamping strip with the presser except during the pressing operation.

We will now describe the operation of the tape or strip-feeding mechanism. The upper end of the arm 5 is extended to form a sector gear or arm 5^a which intermeshes with a pinion 8 that is loosely mounted on the feed roll shaft 9. This pinion is also provided with a projecting circular flange or disk 10 in which is secured an axially projecting pin 11 which normally engages a cooperating pin 12 that is secured to the outer clutch ring 13 of the clutch couple. A yielding spring connection between the pinion 8 and the outer clutch member 13 is afforded by means of a spiral spring 14 one end of which is anchored to the clutch ring and the other of which is anchored to the disk 10 of the pinion 8.

The outer clutch ring 13 is also provided with a radially projecting pin 15 which acts 40 in conjunction with an adjustable stop pin 16 to limit the idling or nonactuating movement of the clutch ring according to the position of the stop pin 16 which stop pin is mounted on an adjustable block 17 movable 45 in an arc-shaped groove 17^a formed in the disk 7^c, and is adjustably clamped in any desired position therein by means of clamping screw 18. This pin 15 also serves to 50 operate the brake on the return or actuating movement of the clutch ring 13 as will be presently explained.

The interior ball clutch member 40 is provided with spring-pressed balls 41 after the usual manner of a ball clutch to allow the outer clutch ring to move in a clockwise direction according to the showing in Figures 4 and 6 without interlocking with the inner clutch member, while on the reverse movement in a counterclockwise direction the two clutch members are frictionally locked together, and the ball clutch head 40 is keyed to the shaft 9 so that on the counterclockwise movement the shaft 9 is rotated in a counterclockwise direction.

65 To prevent the return movement of the

clutch member going too far, we provide an automatic brake mechanism which comprises, as shown in Figures 3 and 5, a brake band 44 anchored at one end to a fixed pin 43 on the head and at its other end secured to a pin 45 on a bell crank lever 46 which is fulcrumed on a fixed pin 47. The bell crank lever 46 is provided with an inwardly projecting pin 48 which projects through a slot in the disk or head 7^c so as to 70 extend into the path of movement of the radial pin on the clutch ring 13 so that on the return or actuating movement of the clutch ring and pin 15, a rocking movement is transmitted to the bell crank lever in a 80 counterclockwise direction, according to the showing in Figures 4 and 6, or a clockwise direction according to the showing in Figure 3, so that the brake band 44 is tightened firmly against the collar 49 secured to the 85 shaft 9 so as to instantly stop the rotation of the feed roll 20.

The device is actuated through a treadle in the following manner.

The lower parallel arm 6 has an extension 90 60 provided with a pin and slot engagement with a vertical plunger 61 carrying at its lower end a disk or head 62 to receive the thrust of a helical spring 63 whereby the head is normally kept raised by means of 95 the pressure of the spring.

The plunger 61 at its lower end rests upon the working arm of a foot treadle 65 which, when depressed by the foot, raises the plunger against the tension of the spring 63 100 thereby forcing the head down toward the bed plate of the work table and at the same time compressing spring 63. When the treadle is released the expansion of the spring 63 raises the head to normal position. 105

The operation of the machine is as follows:

A roll of the stamp bearing tissue tape is placed on the reel 4 and its free end drawn partly around the cross bars 35, 36 in the 110 supporting frame of the head, and is then passed directly beneath the presser foot 37 around the guide 38, thence underneath and partly around the feed roll 20, then back and around feed roll 30, over across shaft 5^b 115 and is then carried back and dropped over the periphery of the coiled tape on the reel. When the head is depressed by the foot treadle 65 the induced movement of the sector arm 5^a rotates the pinion 8 in a clockwise direction, according to Figure 4. Now as the spiral spring acts to press pin 12 secured to the clutch ring normally against pin 11 secured to the disk 10, it will be seen that as the pinion 8 rotates loosely on the 125 shaft 9 in a clockwise direction the spiral spring 14, by its tension, causes pin 12 to follow and keep in contact with said pin 11, but as the clutch is idling on this clockwise movement the ball clutch member does not 130

move. This clockwise rotation of pinion 8 and clutch ring 13 continues until stop pin 15 comes into engagement with adjustable stop pin 16 which arrests the rotative movement of the clutch ring while allowing the pinion to continue its rotation thereby putting extra tension on the spiral spring 14. It will, therefore, be seen that the position of the adjustable stop member 16 determines 10 the initial point from which the return movement of the clutch ring 13 begins.

When the treadle is released the compressed spring 63 raises the head thereby inducing a reverse rotation of the pinion 8 through the sector gear 5^a. The pin 11, therefore, travels back until it engages pin 12 on the clutch ring and thereafter continues to push pin 12 and the clutch ring 13 in a contraclockwise direction until stop pin 15 comes into contact with an actuating pin 48 of the angle lever 46 thereby instantly tightening the brake band and stopping the rotation of the feed roll 20.

It will, therefore, be seen that the descent 25 of the head causes no movement of the shaft 9 through the clutch which idles on this movement but that on the upward movement of the head the clutch members are interlocked or engaged and thereby a reverse 30 rotation is imparted to the shaft 9 and to the feed roll 20, the extent of such reverse rotation being dependent upon the position of the stop pin 16 which governs the point 35 from which the actuating movement of the clutch begins to operate.

The presser foot 37 keeps the tape away from the hot presser 7^b until it comes in contact with the work-supporting bed plate of the table when the presser foot yields under 40 the continued downward movement of the head, thus allowing the presser 7^b which is usually heated, to come in contact with the stamped bearing tape and hot press the stamp against the underlying fabric or article. As soon as the head begins to rise 45 from the table the presser foot or guide once more pushes the tape out of contact with the hot plate, and the stamp strip is then fed forward a predetermined distance according 50 to the adjusted position of the stop pin 16. The slack or waste tape is fed out of the head by means of its frictional contact with the peripheral portion of the reeled tape, as shown at x, Figure 1, so that the 55 hands of the operator are entirely free to handle the work, the feed being both automatic and adjustable and the waste taking care of itself.

It will be seen that the clutch mechanism 60 forms an intermediate ratchet-like connection between the head-supporting means and the tape-feeding roll whereby on each alternate movement, preferably the upward movement of the head, the tape is fed through the head a predetermined distance

according to the adjusted position of the stop pin.

As indicated in Figures 1 and 2, plunger 61 and the helical spring 63 are mounted in a tubular casing 70 which is provided with a small check valve at 71 so as to check the descent of the plunger under the influence of the compressed spring in order to prevent jar or shock.

What we claim is:

1. In a stamp-transferring machine, the combination of a work supporting bed, a presser head movable to and from said head, movable supporting members for moving said head up and down, tape-feeding rolls mounted in said head and operatively connected with one of said movable supporting members to be intermittently actuated thereby in order to feed the tape a predetermined distance on each alternate movement of the head, substantially as described. 75

2. In a stamp-transferring machine, the combination with a work-supporting bed, a presser head mounted on pivotal arms to move to and from the head, tape-feeding 90 mechanism mounted in the head and automatically actuated by engagement with one of said pivoted arms to feed the tape a predetermined distance as the head is moved in order to bring fresh portions of the tape 95 into operative relation to the work, and means for actuating said pivoted arms to raise and lower the head, substantially as described.

3. In a stamp-transferring machine, the combination with a work supporting bed, a presser head, supporting members therefor movable up and down to press the head against the work, a tape-supporting reel, tape feeding rolls mounted in the head and arranged to deliver the waste end of the tape back in contact with the uncoiling tape on the reel in order to draw it out of the machine, said tape feeding rolls being actuated by operative connection with one of the head 105 supporting members, substantially as described. 110

4. In a stamp-transferring machine, the combination with a work-supporting bed, a 115 movable presser head, parallel pivotal arms for supporting said head and carrying it toward and away from the head plate in parallel position, tape-feeding rolls mounted in said head, and means controlled by the movement of the head for operatively connecting one of said tape-feeding rolls with an actuating member on one of said pivoted arms in order to present fresh portions of the tape to the bed on successive stamping operations, substantially as described. 120

5. In a stamp-transferring machine the combination of a work-supporting bed, and a cooperating presser head, pivotally mounted movable supporting members acting to carry the presser to and from the bed in 130

parallel relation, tape-feeding rolls operatively connected with one of said movable supporting members by means of a ratchet clutch to feed the tape intermittently between the presser and the bed, substantially as described.

6. In a stamp-transferring machine, the combination with a work-supporting bed, a presser head mounted on pivotal parallel arms, one of said arms being provided with a sector gear, a pinion adapted to be actuated alternately in opposite directions through engagement with the sector gear as the head is moved to and fro, a tape-feeding roll mounted in said head and means for establishing a driving connection between said pinion and said feed roll on each alternate stroke of the head in order to feed the tape a predetermined distance for each stamping operation, substantially as described.

7. In a stamp-transferring machine the combination of a work-supporting bed, a presser head, means for actuating said head to and from the presser, tape-feeding rolls carried by said head arranged to continuously grip an interposed stamp bearing tape, said rolls being intermittently actuated by the presser actuating means through a ratchet and clutch mechanism connected with the journal of one of said rolls to feed the tape intermittently between the bed and the presser, substantially as described.

8. In a stamp-transferring machine, the combination with a work-supporting bed, a movable presser head, means for supporting said presser head to move toward and away from the bed, feeding roll mechanism for feeding a transfer tape through the head, intermittently actuating mechanism embracing a ratchet clutch operatively connected with the head-supporting means to

rotate the feed roll only when the head is moving in one direction, an adjustable stop member for limiting the rotative movement of said clutch members in order to vary the extent of rotation of the feed roll, and a brake mechanism actuated by said clutch at the end of its tape-feeding movement, substantially as described.

9. In a stamp-transferring machine, the combination of a work-supporting bed, a head movable to and from said bed, a heated presser secured to the head, tape-feeding rolls carried by the head, feed-actuating mechanism embracing a rack and pinion operatively connected and disconnected with said feed rolls on alternate movements of said head by means of a reversely rotated clutch, said rack and pinion being reversely actuated by the alternate movements of the presser head toward and away from said bed, substantially as described.

10. In a stamp-transferring machine, the combination of a work-supporting bed, a pressed movable to and from said bed to hot press an interposed stamp on the work, tape-feeding rolls mounted in the head, feed-actuating means embracing a constantly meshing rack and pinion reversely actuated by the alternate movements of the presser head, a reversely rotated clutch forming an intermittent connection between said rack and pinion and the feed rolls, and an adjustable stop member for limiting the rotative movement of said clutch in order to vary the feeding action, substantially as described.

In witness whereof, we have subscribed the above specification.

TROWBRIDGE MARSTON.
HERBERT E. SERNER.

Witness:

FRANK N. MARSTON.
